UNITED STATES PATENT OFFICE.

MORRIS VICTORSOHN, OF BROOKLYN, NEW YORK.

MOTOR INDICATOR.

Application filed June 10, 1924. Serial No. 719,228.

To all whom it may concern:

Be it known that I, MORRIS VICTORSOHN, a citizen of the United States, residing at Brooklyn, in the county of Kings and State of New York, have invented certain new and useful Improvements in Motor Indicators, of which the following is a full, clear, and exact specification.

This invention relates to mechanical motors especially designed for phonographs, and has for its special object to provide means for indicating the position of the weighted arm, which constitutes the motive power or force for driving the motor, whereby the operator may tell at a glance at a suitable indicator showing on the outside of the casing of the phonograph when the weight 1 should be raised for renewing the energy of the motor.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a section through the casing or cabinet of the phonograph showing the motor in side elevation and in set position, the section being taken on the line I—I of Figure 2.

Figure 2 is a section on the line II—II of Figure 1, and

Figure 3 is a section similar to Figure 1 but showing the positions of the weighted arm, resetting lever, and indicator, when the motor has run down.

The casing or cabinet 1 of the phonograph has a horizontal partition 2 arranged partially across its upper portion, and spaced upright supporting members 4 and 4^a at one side between which the main horizontal bearing shaft 3 of the motor is journaled.

The main gear 5 is mounted on a shaft 3 and has a concentric ratchet portion 6, Figure 1, at one side over which the annular flange 7 of the carrier 8 for the weighted lever 9 extends, said carrier being in disk form and also loosely mounted on the shaft 3. Said carrier has a radially offset chambered portion 10 pivotally carrying the lever or arm 9 which has a weight 11 adjustably mounted

on its outer end. The lever 9 is pivoted at 12 in the chambered portion 10 of the carrier 8, and the inner end of said lever has a ratchet tooth 13 to engage the ratchet portion 6 on the main gear 5, see Figure 1. When the weighted lever moves downward in operation from the position shown in Figure 1 to that shown in Figure 3, the ratchet tooth 13 is held into engagement with the ratchet portion 6 and causes the main gear 5 to turn, but when said weighted lever is being raised in resetting the motor, as will be hereinafter explained, the ratchet tooth 13 is disengaged from said ratchet portion 6 of the main gear.

As shown in Figure 2, the main gear 5 meshes with the gear 14 on a counter shaft 15 extending between the supports 4 and 4^a and turning with another gear 16 which meshes with a gear 17 on another counter shaft 18. Said gear 17 turns with another gear 19 which meshes with a gear 20 on the horizontal shaft 21 carrying a bevel pinion 22 in mesh with another bevel gear 23 on a vertical shaft 24. The bevel gear 23 turns with a gear 25 which meshes with a gear 26 on the spindle 27 which is journaled in the horizontal partition 2 and carries the turntable 28. It will thus be seen that the rotation of the main gear 5 by the downward movement of the weighted arm or lever 9 will be transmitted through the multiplying gear train just described to the turntable which will be given a considerable number of revolutions during the downward movement of said weighted arm.

The resetting of the motor is effected by a lever 29 which is pivotally mounted on the shaft 3 and has its upper end adapted to project through a slot 30 in the top of the cabinet 1. Said lever carries a spring-pressed pawl 31 which normally engages a segmental rack or gear 32 mounted to turn freely on the main shaft 3. This segmental gear has a plane portion 33 provided with a radially extending arm 34 arranged below the weighted arm or lever 9 and connected thereto by a link 35. Because of the connections between the parts just described, it will be noted that as the weighted lever arm 9 moves downward the resetting lever 29 swings from left to right, as shown in Figure 1, and that by swinging said resetting lever from right to left the weighted lever arm 9 will be raised.

The upper end portion 36 of the lever 29 is swiveled to the main portion thereof, as at 37, Figures 1 and 3, and said upper end portion 36 carries a rock arm 38 connected to a 5 push rod 39 guided in a bracket 40 on the main portion of the lever and extending to a point just above the free end of the pawl 31. Said pawl may be thus released from the segmental gear 32 by swinging said upper end portion 36 on the lever 29 to the right, as indicated in Figure 1.

The slot 30 in the top of the cabinet may be closed by a cover plate 41 hinged at 42. The upper end portion 36 of the lever 29 15 carries a handle 43 pivoted thereto at 44 just below the top of the casing 1. When raised, as shown in Figure 3, said handle 43 extends through the slot 30 in the top of the casing where it may be grasped for resetting 20 the motor. When not in use, however, said handle may be folded down into the position indicated in Figure 1 where it lies below the lever of the top of the casing and may be covered by the hinged cover 41. The handle 25 43 is rule-jointed to the upper end portion 36 of the lever 29, so that said lever may be moved from right to left for resetting the motor when said handle is raised or extended into line with said lever. A spring 45 is 30 attached to the lever and adapted to bear against the handle when raised for automatically folding or collapsing the latter when released. Of course, when the handle 35 is grasped by the operator for resetting the motor, the spring 45 is placed under sufficient tension to throw said handle over as soon as it is released.

In order to regulate the throw of the weighted arm 9 in resetting the motor, so 40 that the swing of said arm may be accommodated within casings or cabinets of different sizes, the arm 34 and link 35 may either or both be made extensible. Said arm 34, for instance, may comprise telescopic sections 46 and 47, the latter having a socket to receive the former, and a bolt 48 may be passed through a slot 49 in said member 47 for adjustably securing the sections together. The link 35 may be similarly 45 formed of telescopic sections 50 and 51, the latter having a socket with slots 52 in its walls through which a bolt 53 extends for adjustably securing said sections together.

In order to vary the power developed by 55 the falling of the weighted arm 9, the weight 11 is adjustably mounted on the outer end portion of said arm so that it may be secured thereto at different distances from the fulcrum of said arm, that is, the shaft 3. 60 This adjustment of the weight of the arm may be effected by providing longitudinally extending slots 54 in the forked free end of said arm 9, and mounting the weight 11 in said fork between said prongs with a bolt 65 55 extending from opposite sides of the

weight through said slots, said bolt being fitted with suitable nuts by which it may be tightened for clamping said weight at any desired point along said arm.

To indicate the position of the weighted 70 arm 9 within the cabinet 1, a dial 56 is mounted on top of said cabinet above a slot 57 therein, and from the shaft 58 carrying the hand or indicator needle 59 and a swinging arm 60 depends through the slot 57 into the interior of the cabinet. The lower end of said swinging arm 60 is provided with an open loop 61 into which the rounded upper end 62 of an intermediately pivoted lever 63 extends. Said lever 63 is intermediately pivoted to the sides of the cabinet at 64 and its other end extends into juxtaposition to the segmental gear 32 of the motor resetting device. A segmental cam 65 is formed on the side of said segmental gear 32, and the extremity of the lower end portion 66 of the lever 63 is bent, as at 67, to engage said cam so that as the cam moves with the resetting device during the movement of the weighted arm 9, the lever 63 90 is swung and the position of the indicator needle 59 on the dial 56 correspondingly changed. Thus, when the weighted lever 9 is raised or in set position, the needle of the indicator will be in vertical position, as 95 shown in Figure 1, whereas when the weighted arm 9 has swung down to the position indicated in Figure 5, showing that the motor needs resetting, the needle 59 of the indicator is deflected to the left and the operator is thus advised of the necessity for 100 resetting the motor.

I claim:

1. The combination with a mechanical motor including a swinging weight carrying arm, of an indicator operatively connected to the motor for showing the position of said weighted arm whereby the operator may be advised as to when it is necessary to reset said lever. 105

2. The combination with a member to be rotated, of a weighted arm for actuating said member, an indicator, and means of connection between said indicator and said member for automatically showing by the indicator changes in position of said weighted arm. 110

3. The combination with a member to be rotated, of a weighted arm for actuating said member, an indicator, a cam on said member, and means operatively extending between said cam and indicator for automatically showing on the latter changes in position of the weighted arm. 120

4. The combination with a member to be rotated, of a weighted arm for actuating the same, a cam on said member, an indicator dial, a needle rotatably mounted on said dial, and an intermediately pivoted lever, operatively extending between said cam and 125

needle for automatically moving the latter to show corresponding movements of the weighted lever.

5. The combination with a member to be rotated, of a weighted lever for actuating the same, a cabinet for enclosing said parts, an indicator on the outside of the cabinet, and means for automatically showing on the indicator changes of movement of said

10 weighted arm.

6. The combination with a member to be rotated, of a weighted lever for actuating the same, a cabinet for enclosing said parts, an indicator on the outside of the cabinet, 15 means for automatically showing on the indicator changes of movement of said weighted arm, and means for resetting said arm when required.

7. The combination with a member to be rotated, of a weighted arm for actuating the same, an indicator dial, a needle rotatably mounted on said dial, an arm depending from said needle and having an opened loop 20 at its lower end, a lever having one end

loosely fitted in said loop, and a cam on 25 the rotatable member engaged by the other end of said lever, whereby movements of the weighted arm will be shown by corresponding movements of the needle on said indicator dial.

8. The combination with a motor to be rotated, of a weighted arm for actuating the same, a cabinet for enclosing said parts, an indicator dial mounted on the outside 30 of said cabinet, a pivoted needle mounted 35 on said dial, an arm depending from said needle through a slot in the cabinet and having an open loop at its lower end, a lever having one end loosely fitted in said loop, and a cam on 40 the rotatable member of the motor engaged by the other end of said lever, whereby changes in movement of said weighted arm will be shown by corresponding changes in the position of the needle on 45 said indicator dial.

In testimony whereof I have signed my name to this specification.

MORRIS VICTORSOHN.
